US0D1040200S

(12) **United States Design Patent** (10) **Patent No.:** **US D1,040,200 S**
(45) **Date of Patent:** **** Aug. 27, 2024**

(54) **BEARING HOUSING**

(71) Applicants: **Marco Fenu**, Hawley, MN (US); **Lucas Hoffman**, Detroit Lakes, MN (US)

(72) Inventors: **Marco Fenu**, Hawley, MN (US); **Lucas Hoffman**, Detroit Lakes, MN (US)

(**) Term: **15 Years**

(21) Appl. No.: **29/832,476**

(22) Filed: **Mar. 28, 2022**

(51) LOC (14) Cl. **15-09**

(52) U.S. Cl.

USPC **D15/143**

(57) **CLAIM**

The ornamental design for a bearing housing, as shown and described.

DESCRIPTION

FIG. 1 is a front-bottom perspective view illustrating our design for a bearing housing.

FIG. 2 is a bottom view thereof.

FIG. 3 is a top view thereof.

FIG. 4 is a front view thereof.

FIG. 5 is a rear view thereof.

FIG. 6 is a right-side view thereof.

FIG. 7 is a left-side view thereof; and,

FIG. 8 is a rear perspective view thereof.

The broken lines in the Figures showing the bearing insert, lubrication fitting and fastener form no part of the claimed design.

1 Claim, 8 Drawing Sheets
